UNITED STATES PATENT OFFICE.

ARCHIMÈDE BATAILLE, OF TOULOUSE, FRANCE.

CUTTING MACHINE.

Application filed December 1, 1925, Serial No. 72,436, and in France December 17, 1924.

This invention refers to machines comprising a press and a tool for cutting or working in any manner upon the material being pressed; and relates more particularly, although not exclusively, to machines of this type for cutting or clipping paper, cardboard and other like material, as it is in the case of such material that the machine would appear to offer the greatest advantages.

It has for its object, to so construct such machines that they respond in a more satisfactory manner than has hitherto been the case to practical industrial requirements.

According to the general principle of the invention, machines of the class in question are so constructed that there is interposed in the driving train between the press on the one hand and the tool on the other hand, epicyclic gearing, so that suitable pressure on a pile of the material to be treated can be secured, irrespective of the height of such pile within the limits imposed by the size of the machine. Such suitable pressure is secured during the entire period of operation of the device, without any adjustment of the press with respect to the height of the pile of material, in order to ensure the necessary pressure upon the said pile. Use is made of the reaction resulting from the resistance encountered by the moving part or parts of the device, as a force for ensuring the necessary pressure for pressing and maintaining the action upon the said materials, the said force increasing with the resistance encountered by the tool. The pressure exerted by the press on the materials to be treated can be varied at will according to the nature of the work to be performed.

The invention consists, in addition to the principal feature already stated, of certain other features which are preferably utilized at the same time and which will be more fully described hereafter.

It includes more particularly certain methods of application (those in which the invention is applied to cutting or trimming machines for paper, cardboard and like material) and to certain constructional embed-

ments of its principles (which will be more fully set out hereafter); and it includes in particular, and as new industrial products, machines of the class in question including the application of such arrangements, special parts and tools adapted for their construction.

The invention will, in any case, be well understood by means of the following description, as well as from the annexed drawings, which description and drawings are, it is to be clearly understood, merely given by way of example.

Fig. 1 is a diagrammatic vertical elevation partially in section, of the essential parts of a machine constructed according to my invention, this view being taken on the line 1—1 of Fig. 2.

Fig. 2 is a vertical section on the line 2—2 of Fig. 3.

Fig. 3 is a detail view showing another embodiment of the brake control mechanism.

According to the invention, and more particularly according to those methods of application and to those constructional embodiments of its various features to which it would appear that preference should be given, in constructing a machine for cutting piles of paper, to the following principles of construction.

The general construction includes a framework 1 of suitable shape, size, and strength. 2 is a primary shaft mounted in bearings in the framework, horizontally for instance. This shaft has communicated to one end thereof the motion from a motor (not shown). The primary shaft 2 carries a pinion 3 at the other end thereof.

4 is a gear or toothed annulus adapted to mesh with the pinion 3 and mounted loosely with respect to the first aligned shaft 5, which is parallel to the shaft 2 and is mounted in bearings on the framework. The annulus 4 is fixed to a casing 6 revolute with respect to the shaft 5 and also mounted upon and revolute with respect to a second aligned shaft 7 separate therefrom, located in alignment with shaft 5 and also mounted

in bearings on the framework. This casing 6 is adapted to contain a set of epicyclic gearing of any desired type, for instance of the planetary type, and consisting of two planet bevel gears 8 fixed respectively to the shafts 5 and 7 and by two sun bevel gears 9 mounted on spindles perpendicular to the previously mentioned shafts and carried by the said casing, so that said sun bevel gears 16 can freely revolve in casing 6.

10 are two vertical racks fixed to the platen 11 of the press and adapted to mesh respectively with two gears 12 fixed upon a shaft parallel to those previously mentioned and mounted in bearings in the framework. One of gears 12 meshes with a pinion 13 fixed to the shaft 7.

14 is another shaft parallel to those previously mentioned, mounted in bearings in the framework and adapted to be rotated by the shaft 5 by means of two gears 15 and 16, meshing with one another and fixed respectively upon the said shafts 14 and 5. The shaft 14 operates the vertically movable knife 20 by means of two crank pins 17 and two connecting rods 19. One of said pins 17 is mounted upon the toothed wheel 15, and the other of them is mounted upon a disc 18 which will be mentioned hereafter. The slide which carries the vertically movable knife 20 and the plate 11 of the press, is located above a horizontal table 21 carried by the framework.

22 is a fly wheel mounted on the shaft 5 and adapted as will be seen hereafter to be acted upon by a brake or to be allowed to run freely.

Means are also provided for connecting the shaft 2 to the driving shaft or for disconnecting it therefrom. These means include for instance, a member 23 connected to said shaft 2 by a longitudinally slidable key and adapted to be connected to the said driving shaft by any suitable clutch means. Such means may for instance include conical clutch elements, and member 23 may be released when it is moved into a conical recess 24 provided for the purpose in the framework.

25 is a lever pivoted to the framework and furnished with a fork at one of its extremities. This fork engages a groove provided for the purpose in the member 23 so as to actuate said member 23 to and fro. At its other end the lever 25 is provided with an edge adapted to be engaged by or released from an engaging hook 26. The disc 18 is provided with a boss or projection which operates upon the said hook 26 to disconnect it from lever 25.

60 The spring 27 then moves member 23 into the inoperative position so that shaft 2 is disconnected from the drawing shaft.

Means are provided for enabling the fly wheel 22 to be subjected more or less to a braking action or to be allowed to run freely.

The means in question may be of various kinds, but may be for example of one of the following:

As shown in Figs. 1 and 2, the fly wheel 22 is furnished with two brake shoes 28 pivoted together by means of a pivot pin 29 fixed to the framework. 30 is a cam member adapted to operate these brake shoes and connected to a lever 31.

A cam 32 is mounted on shaft 14, half of said cam having a circular contour, the other half thereof being tapered as shown in Fig. 1, the greatest radius of said tapered portion being less than the radius of said circular portion. A spring 33 tends to force the brake shoes 28 into the operative or braking position. Since the movement of the brake shoes turns the cam 30 and the attached lever 31, said spring 37 causes lever 31 to contact with cam 32. Hence, the brake shoes are moved to the inoperative position during substantially a half-revolution of the shaft 14, when the lever 31 is moved in a counter-clockwise direction by cam 32. Likewise, the circular portion of cam 32 forces lever 31 to a position in which cam 30 forces the brake shoes 28 to the inoperative position, during the second half-revolution of shaft 14, and while the crank pins 17 are moving from lower dead center to upper dead center. The brake pressure is greater when crank pins 17 are in substantially the position shown in Fig. 1, due to the shape of cam 32.

As an alternative, and as shown at Fig. 3, there may be provided an arrangement such as that already described, that is to say two brake shoes 28, a cam 30 for operating these brake shoes, a lever 31, a cam 32 and a spring 33 for forcing the brake shoes to operative position, but with this difference that the free extremity of the lever 31 in this case enters a notch 36 as hereafter mentioned. In addition an auxiliary mechanism is provided including a bell-crank lever 34 pivoted, to a fixed portion of the framework by means of a pivot pin 35 parallel to the shafts previously mentioned. This bell-crank lever has one of its arms provided with the notch 36 just mentioned. When the lever 31 is engaged by the notched end of lever 34, said lever 34 is kept in this position by a suitably arranged tension spring 37. The other arm of the said lever 34 is adapted to be moved in the direction in which it liberates the lever 31 by an arm 38 attached to the hub of one of the gears 12. 39 is a lever pivoted at 40 to a fixed part of the framework, and adapted to oscillate under the action of the cam 32, similar to the lever 31 of the previous arrangement. This lever 39 is also pivotally connected to a link 41, which is pivoted to a lever 42 mounted loosely on the shaft of cam 30, and provided with a projecting finger 43 adapted at a predetermined moment to come into

contact with the lever 31. When the lever 31 is held by the notch 36 of the bent lever 34, as long as the said bent lever is not operated by the arm 38, the brake is not brought into action, whilst when the said arm comes into contact with the said bent lever, the lever 31 is liberated and the brake is applied by means of the spring 33.

The cam 32' then comes into operation and causes the lever 42 to oscillate in a direction in which the finger 43 presses against the lever 31 in such a direction that it causes the braking operation to cease and brings back the said lever 31 into its locked position in the notch in the bent lever.

When a machine has been constructed and built in a suitable manner on the foregoing lines, supposing the same to be properly assembled, the operation will be as follows.

Assuming the clutch mechanism is of the type illustrated in Fig. 2, when the lever 25 pushes the member 23 to connect shaft 2 to the driving shaft, the said lever engages with the hook 26 and the shaft 2 commences to turn in a direction shown by the arrow drawn around the same on Fig. 2. The shaft 5 which is at this time under the influence of the brake (the brake having been applied the more strongly in proportion as it is desired to exert greater pressure by means of the press) cannot turn, and it is the shaft 7 which commences to turn in the direction of the arrow drawn around the same on the aforesaid Fig. 2. This causes the descent of the platen 11, by means of the racks 10 operated by the toothed wheels 12, which are actuated by the pinion 13.

At the moment when the resistance of the pile of paper 44 to be pressed becomes sufficient to overcome the force exerted on platen 11 due to the braking action exerted on the fly wheel 22, the platen 11 stops. The revolution of shaft 7 is thus stopped and it is the shaft 5 which now commences to turn, operating the knife 20 by means of the pinion 16, the gear 15 fixed on the shaft 14 and the connecting rods 19 and pins 17. The knife is thus caused to cut the pile of paper 44, the result being to automatically increase the pressure exerted by the press on the paper, and this excess of pressure is proportional to the resistance opposed to the movement of said knife.

At the moment when the said knife completes the cutting operation, that is to say when the two crank pins 17 have passed their lower dead point, the cam 32' (Fig. 3) pushes upon the lever 39, and, by means of the link 41 of the lever 42 and the finger 43, it brings the lever 31 into the notch 36 of the lever 34. The brake shoes are then disengaged and have no further action upon the fly wheel 22. At this time there is no

pressure being exerted upon the paper except that due to the edge of the knife and the amount of force necessary for continuing the movement of the working parts of the machine; in other words, the actual pressure on the paper is then practically zero.

The machine continues to work and the blade rises. When the crank pins 17 are adjacent their upper dead point, the projection on the plate 18 contacts with the hook member 26 and liberates the lever 25, which lever, under the influence of a spring 27 operates the member 23 and pushes it into the recess 24 in the framework 1.

The movements of shaft 2, the pinion 3, the wheel 4 and the casing 6 are thus stopped.

The shaft 5 continues to turn because the fly wheel 22 which is free at this moment, the cam 32 having disengaged the brake shoes after the cutting through of the pile of paper 44, as previously explained.

The shaft 5 continues to turn, and as the movement of casing 6 has been stopped, the planet members 8 and the sun members 9 function like ordinary bevel gears. The shaft 7 is thus turned in a direction opposite to that of the arrow drawn around the said shaft, and the platen rises until it reaches the end of its upstroke, and the arm 38 (Fig. 3) abuts the lever 34 and moves it to free the lever 31 from the notch 36. At this moment, under the action of the spring 33, the brake shoes come into contact with the fly wheel 22 and lock it in the starting position.

Other means may be adopted for raising the press, but in all cases an epicyclic or planetary gear train is employed. For instance, a system of counterbalance weights or of springs might be used for obtaining the desired results. As a further example, a cam might be keyed upon the shaft carrying the crank pin operating any of the transmission members between the planet shaft 7 and the racks 10, or the operation might be direct, or again levers or any other types of transmission devices might be employed suitable for raising the press, the movement being then of a positive nature and the only inconvenience being the possible increase in the velocity of the other planet shaft. It will be noted that the epicyclic gear comprises separate elements which are separately connected to the press and knife.

It is to be carefully noted that the invention is constituted solely by the interposition in the driving train of machines for the uses indicated, of any type whatever of epicyclic or planetary gearing, the object being to give the following advantages to the machine:

Elimination of all preliminary regulation of the press with respect to height.

Stoppage of the press at any point of its course according to the thickness of the material to be cut.

5 Pressure adjustable at will according to the work to be carried out.

Increase in the automatic character of the working of the press, the pressure exerted being increased as a function of the resistance encountered by the knife during its cutting stroke.

10 Great economy in driving power, since a very large proportion of the pressure is produced by the reaction due to the cutting action of the blade.

15 As will be clearly understood, and as has already been pointed out, the invention is not limited in any way to those applications or to those constructional embodiments of its various principles which have been more 20 particularly described herein. It includes all modifications coming within a fair interpretation of the claims, and it is to be observed that the transmission mechanisms may be of any desired description, those 25 shown on the drawings being represented with no other object than to facilitate the understanding of the invention and the important part played by the epicyclic gearing in the machine.

30 What I claim and desire to secure by Letters Patent of the United States of America is:—

1. In a machine of the class described, the combination of a movable clamping member, 35 a movable cutting member, driving means connected to said clamping member and to said cutting member by a common train of planetary gearing having separate elements 40 separately connected to said clamping member and to said cutting member, and brake means adapted to check the movement of one of the elements of said train of gearing.

2. In a machine of the class described, the 45 combination of a movable clamping member, a movable cutting member, driving means connected to said clamping member and to said cutting member by a common train of planetary gearing having separate elements 50 separately connected to said clamping member and said cutting member, and brake means adapted to check the movement of that element of said train of gearing which is connected to the cutting member.

55 3. In a machine of the class described, the combination of a movable clamping member, a movable cutting member, driving means connected to said clamping member and to said cutting member by a common train of 60 planetary gearing having separate elements separately connected to said clamping member and to said cutting member, brake means

adapted to check the movement of the element connected to said clamping member, and control means for said brake means connected to said cutting member. 65

4. In a machine of the class described, the combination of a movable clamping member, a movable cutting member, a primary shaft connected to said clamping member and said cutting member by a common train 70 of planetary gearing having separate elements separately connected to said clamping member and to said cutting member, driving means for said primary shaft, and means 75 effective to automatically stop the movement of said primary shaft when said clamping member is above its operative pressing position.

5. In a machine of the class described, the combination of a table, a movable clamping member, a movable cutting member, driving means connected to said clamping member and to said cutting member by a common train of planetary gearing having separate elements 80 separately connected to said clamping member and to said cutting member, brake means adapted to check the movement of that element of said gearing which is connected to the cutting member, and automatic control means for said brake means connected to said cutting member and effective to release said brake means substantially during the movement of said cutting means away from said table. 85

6. In a machine of the class described, a reciprocable clamping member, reciprocating means connected to said clamping member, a rotatable driving shaft connected to said reciprocating means, a movable cutting member, actuating means connected to said movable cutting member, a rotatable driving shaft connected to said actuating means, a gear connected in planetary driving relation to each of the rotatable driving shafts, and means for driving said last named gear. 100

7. In a machine of the class described, a reciprocable clamping member, reciprocating means connected to said clamping member, a rotatable driving shaft connected to said reciprocating means, a movable cutting member, actuating means connected to said movable cutting member, a rotatable shaft connected to said actuating means, a fly-wheel mounted on said last named rotatable shaft, brake means associated with said fly-wheel, a gear connected in planetary driving relation to each of the rotatable driving shafts, and means for driving said last named gear. 110

115 In testimony whereof I have hereunto set my hand.

ARCHIMÈDE BATAILLE.
